SELF-CENTERING SPINDLE FOR SPINNING FRAMES

Joseph Raboission, Soultz, France, assignor to
 Society: "Manufacture Alsacienne de Broches,
 Anciennement les Fils d'Edouard Latscha S. a.
 r. L.", Soultz (Haut-Rhin), France

Application February 18, 1937, Serial No. 126,496
 In France March 6, 1936

2 Claims. (Cl. 308—149)

The present invention relates to spindles of the kind known as "self-centering" or "flexible" spindles, used in spinning frames, twisting mills, silk throwing machines, and winding machines. It provides improvements in the flexible sleeve-bearings of said spindles, with a view to obviating the disadvantages which have existed until the present, in said bearings.

These improvements are hereinafter described and shown in the drawing as applied to a gravity spindle of any well-known kind.

Figure 1 is a view in diametrical section of a flexible spindle, having an improved sleeve-bearing of the flexible kind improved according to the invention.

Figure 2 is an enlarged partial view, on a diametrical section of the sleeve-bearing, and of its bolster of the kind with closed foot.

Figure 3 is a similar view with the bolster of the kind with open foot.

The gravity spindle, to the sleeve-bearing of which are applied the improvements forming the subject matter of the invention, is made in the usual fashion.

1 is the spindle itself of which the lower extremity forming pivot 1' rests in the footstep formed at the lower end of the bolster 2, of which the upper part is formed as an extension constituting a socket 3.

4 is the bolster case which is fixed in the spindle rail of a spinning frame or the like, 5 being the whirl or wharve fixed on the spindle proper 1, in usual fashion, above the bolster 2.

The improvements forming the subject matter of the present invention, consist in the following:

In the first place, in having the extremity of the bolster 2 of the spindle 1 bear in a mount 6 cup shaped like, with spherical bottom 6' disposed in the bolster case 4, and in having the said spherical bottom rest on a corresponding spherical hollow 4', formed in the bottom of the bolster case 4, the setting of the bolster 2 in its mount 6 is characterised in that, in combination with the spherical form of the bottom 6' of the said cup 6 and that of the hollow 4' in the bolster case 4, the extremity 1' forming a pivot for the spindle 1 is situated at the centre 7 or approximately at the centre of the sphere of the bottom 6' of the cup shaped mount 6.

In the second place, concerning the spring used in flexible bearings, in substituting for a metallic spring of any kind whatever, an elastic unsplittable ring 8 of rubber, tight set on the socket 3 of the bolster 2 and without play in the bolster case 4.

Owing to these improvements, the socket or

extension 3 of the bolster 2 is perfectly centred, without play, in the bolster case 4, but with all the flexibility of the rubber reacting progressively in direct ratio to the effort.

The fact that the centre of the sphere of the bottom 6' of the mount 6 is situated, by this construction, near the extremity of the pivot 1' of the spindle proper 1, allows the mass in rotation to achieve a self-centering effect, without any constraint for the spindle proper 1, about an axis 10 passing through the point 1'.

The functioning of this spindle is therefore analogous to that of a spinning top.

The gyratory movement which results, is lessened by the rubber ring 8. This ring, due to the fact of its adherence on the surface of the bolster case 4, reacts to pressure, but does not take the movement of precession which would exist with a flexible metallic spring. Practically there is no gyratory movement to be noticed.

Moreover, the mount 6, forming a sort of ball-and-socket-joint, not being integral with the bolster, allows of a certain slow axial displacement favouring the complementary centering of the mass and limiting its amplitude.

The weight of the elements and the reaction of the elastic ring 8, tend to brake the bolster 2 and to return it into its theoretical position when the effect of want of balance is reduced or disappears.

In the matter of the setting of the mount 6 in a bolster case 4 with open foot (Figure 3) the lower end 9 of the bolster case 4 is made separable. Tightness is assured by a ring 10 of rubber (oil resistant) or in leather, compressed by a blocking member 11. The separable end 9 may also be threaded exteriorly and screwed directly to the interior of bolster 4 just as it is formed for greaser plugs with multiple threads. The open foot affords as another advantage a more easy drainage.

I claim:

1. In a bearing for a self-centering spindle for spinning frames or the like, a rotatable spindle having a pointed pivot end, a bolster and step in one piece having an externally conical bottom the lower inner end of which receives the pointed end of the spindle while its upper part forms a socket, and a bolster case in which is located the sleeve, the lower inner end of said bolster case being spherical internally, a cup shaped mount situated intermediate the conical bottom of the bolster and the spherical lower end of the bolster case, said mount being internally conical to receive and fit the external conical bottom of the bolster and being spherical externally to bear

and fit the spherical lower end of the bolster case having the same radius, and one single element for preventing and limiting the lateral and axial displacements and the rotation of the bolster in the bolster case, said element being constituted by a continuous rubber ring between the upper part of the bolster case and the socket of the bolster upon which said ring is tightly applied.

2. A bearing as claimed in claim 1 characterized in that the pointed end of the rotatable spindle is located at the center of the spherical bottom of said cup-shaped mount and the spherical lower end of said bolster case.

JOSEPH RABOISSON.
